HYPODERMIC SYRINGE AND ASPIRATING AMPOULE THEREOF

Marshall L. Lockhart, Rutherford, N. J., assignor to The Compute Corporation, Rutherford, N. J., a corporation of New Jersey

Application December 1, 1951, Serial No. 259,471

7 Claims. (Cl. 128—218)

The present invention relates to hypodermic syringes for subcutaneous injection of ampule contents and, more particularly, to such devices equipped with means readily to provide a show of blood for ready guidance of proper subcutaneous insertion as referred to in my prior Patent No. 2,556,331 of June 12, 1951.

A general object of the present invention is to provide such hypodermic syringe structures, and parts thereof, which are unusually simple in construction, readily produced on an economical basis, and easily assembled and efficiently used; and which feature ampule aspirating means effectively to assure a show of blood.

A more specific object of the present invention is to provide in such hypodermic syringe devices ampule aspirating bulb means serving to close off one end of an ampule having its other end closed off by a needle-pierceable piston plug to be driven forward into said ampule by a piston post in the casing as the ampule is telescoped therewith, the aspirating bulb means effectively serving in a simple manner as a thrust member for the ampule to telescope the latter into the casing for expulsion of contents through the bore of a double-ended hollow needle having its inner end extending beyond the post for puncture of the piston plug.

Another object of the present invention is to provide such ampule structure for that type of hypodermic syringe which is equipped with blood telltale piston plug means that will facilitate observation of a show of blood.

An additional object of the present invention is to provide structural embodiments of such hypodermic syringe devices and aspirating ampules thereof which are readily and economically constructed and which permit efficient use, operation and functioning thereof, as will be more fully apparent from the following descriptions of the embodiments illustrated by way of example in the accompanying drawing.

Other objects of the invention will in part be obvious and will in part appear hereinafter.

The invention accordingly comprises the features of construction, combination of elements and arrangement of parts, which will be exemplified in the constructions hereinafter set forth, and the scope of the invention will be indicated in the claims.

For a fuller understanding of the nature and objects of the invention, reference should be had to the following detailed description taken in connection with the accompanying drawing, in which:

Fig. 1 is an axial section of an embodiment of the hypodermic syringe casing designed to receive and employ as barrel and piston means ampules of the present invention, one embodiment of which is shown therein in section in axially aligned position to be telescoped into the casing;

Fig. 2 is an enlarged axial section of the ampule shown in Fig. 1, showing its piston plug seated against the casing piston post (partly in section and broken away) with puncture of the plug by the needle and illustrating aspiration of the ampule for a show of blood by manipulation of the ampule thrust cap;

Fig. 3 is a sectional view similar to Fig. 2, but with all parts of the piston post omitted, illustrating aspirating action with use of another form of the piston plug particularly designed for facilitating observation of a show of blood, with parts of the plug in elevation and parts in section;

Fig. 4 is a sectional detail of the left end of Fig. 3 showing in elevation the blood telltale plug thereof as

2

viewed from a point at 90° to the position from which it is viewed in Fig. 3;

Fig. 5 is an elevational view of the structure shown in Fig. 4 as viewed from the right end thereof, with the ampule tube sectioned;

Fig. 6 is a sectional view similar to Fig. 4, illustrating a modified form of blood telltale piston plug structure shown partly in section; and

Fig. 7 is a sectional view taken substantially on line 7—7 of Fig. 6.

Referring to the drawing, in which like numerals identify similar parts throughout, it will be seen that an embodiment of the present invention may comprise the hypodermic syringe assembly shown in Fig. 1 consisting of a socketed casing unit 10 carrying a double-ended hollow hypodermic needle or cannula 11 and a loaded ampule 12. The casing unit 10 may conveniently be formed as a molded cylindrical tubular body of suitable rigid plastic material closed off at one end to provide a head 13, through which is anchored, preferably in the molding, the mid-portion of a hollow needle or cannula 11. A piston post 14 is concentrically located in the cylindrical casing 10 and extends inwardly coaxially from the head 13. Conveniently such piston post structure 14 may be, as shown, a cup-shaped or cylindrical structure arranged about the needle, with the latter extending therethrough so that the needle inner end 15 is located appreciably beyond the inner end 16 of the piston post. Casing 10 may include laterally-extending engaging structure 17, either in the form of opposed wings or a circular flange, to serve as finger-engaging means or to facilitate grasp thereof. Injection hollow needle 11 has an outer injecting end 18. The inner wall of cylindrical casing 10 and the outer wall of cylindrical piston post 14 provide therebetween a receptive circular or cylindrical groove 100 circumambient of the post and into which the end of a tubular barrel or ampule structure may be slid.

The loaded ampule 12 preferably comprises an elongated section 19 of cylindrical tubing of light-transmitting material, preferably transparent, such as glass, substantially rigid plastic or the like. Ampule tube 19 is closed at its leading end 20 by a piston plug 21 of any suitable needle-pierceable material, such as rubber, elastic plastic, etc., slidably received therein as shown. Such piston plug 21 preferably has the usual axial pocket or recess 22 to define a relatively thin end wall or outer sealing portion 23 through which the inner needle end 15 is readily pierceable for communication of the bore of the latter with the chamber provided by the interior of ampule tube 19. The trailing or outer end 24 of ampule tube 19 is closed off by thrust means 25 to confine within the ampule a body 26 of injectable medicinal liquid.

The thrust means 25 is preferably in the form of a cap, having an inner cylindrical tubular portion or hollow neck formed by a concentric coaxially-extending circular flange 26 which may be telescoped with the ampule tube end 24 in any suitable manner, such as by being tightly received therein, as shown. Thrust cap 25 preferably has its outer end or face 27 suitably contoured for facilitating engagement thereof by the operator's thumb. The central or middle portion 28 of cap end 27 constitutes a relatively-thin, flexible cross wall closing off an axial pocket 29 in communication with the ampule chamber in which liquid body 26 is confined, so that thrust cap 25 also may serve as an aspirating bulb, as will be more fully understood by reference to Fig. 2. As shown, the bore 30 of hollow neck 26 communicates through a hole 31 with partially collapsible pocket chamber 29, to form an aspirating bulb in the preferred form of the thrust cap 25.

In operation, the operator thrusts the injecting outer end 18 of the needle 11 subcutaneously into the patient and aligns a selected loaded ampule 12 with the open end of the casing 10, as shown in Fig. 1. The leading end 20 of ampule 12 is moved forward to the dot-dash line position shown at 32 in Fig. 1 so that the inner end 15 of the needle pierces through the piston plug end wall 23 to the pocket 22 to extend beyond the inner end 33 of the piston plug to an observable position, such

as indicated in Fig. 2. In such relative positions, the outer end 16 of the piston post 14 engages the outer end 330 of the piston plug, as there indicated. The operator then with his thumb or a finger applies pressure to the bulb cross wall 28 to cause it to flex inwardly from the outer full line position shown in Fig. 1 indicated in dotted lines at 34 in Fig. 2, to the inner full line position shown in Fig. 2. As a result, the internal capacity of the ampule chamber is reduced, and when the elastic flexible cross wall 28 is released to permit it to snap out to the dotted line outer position 34, an aspirating action is developed so that blood will be drawn through the needle bore to be observable at the needle inner end 15 if the needle bore is in communication with a vein. Such aspirating action is indicated by the arrows at 35.

If the liquid medicament is intended for intravenous injection, such show of blood will assure the operator that he may properly proceed with the injection by thrusting the loaded ampule 12 forward with pressure applied thereto, such as by the digit-engageable thrust cap 25, to telescope ampule tube 19 down into the circular recess 100 with piston post 14 sliding piston plug 21 back into the ampule tube. As the ampule tube 19 is so telescoped into the casing 10, the body 26 of liquid medicament will be expelled through the needle bore. If, however, the medicinal preparation is intended for intramuscular injection, then such preliminary show of blood will, of course, dictate to the operator removal of the injecting end 18 of the needle and relocation thereof.

Some medicinal liquid preparations are of a relatively high degree of opacity, and thus may make difficult observation of a show of blood at 35 at the inner end of the needle. Such difficulty may be readily overcome in a manner suggested in Fig. 3. As therein proposed, piston plug 21 of the Figs. 1 and 2 embodiment may be replaced by a blood telltale piston plug 121. Such blood telltale plug 121 may comprise a substantially cylindrical piston plug body of suitable rubber, elastic plastic material, or the like, having in one side thereof a transversely-extending notch 122 deep enough to bring it into communication with the bore of the hypodermic needle 11 when the foreshortened inner end 115 of the latter is thrust through the outer portion 123 of the piston plug in the manner indicated in Fig. 3. Communication between the pocket or chamber provided by the notch 122 and the interior of the ampule tube 19 may be effected by means of a longitudinally-arranged groove 36 extending from that notch to the inner end 133 of the blood telltale piston plug 121. Of course, a plurality of such grooves may be provided as is illustrated in Fig. 6, and such groove 36 obviously need not extend substantially parallel to the axis of the plug.

Such blood telltale piston plug structure 121 and its action will be readily understood by reference to Figs. 3, 4 and 5. Observation of flowing blood is facilitated by confining it to a channel juxtaposed to the inner face of a portion of the ampule tube 19 as defined by pocket 122 and groove 36 for ready observation at that point upon aspiration of the ampule in a manner similar to that indicated above.

Blood telltale piston plug structure may be provided in a modified form, such as that proposed in Figs. 6 and 7. One section 221 of such piston plug structure may be similar to the piston plug of the Figs. 1 and 2 embodiment but possibly somewhat shallower or thinner as shown, and formed with a similar recess or cup 222 to which the inner end 115 of the hypodermic needle 11 extends after thrust through the outer portion 23 of that plug section. A second rear plug section 38 is provided to seat against the rear face 233 of plug section 221. Such rear plug section 38 may, as will be understood from Figs. 6 and 7, have the circular edge of its front face 39 chamfered off at 40 to provide a circular groove or closed circumambient or annular channel when both plug sections 221 and 38 are disposed within the ampule tube 19. Annular channel 40 is communicated with recess 222 by means of a cross groove 41. Communication between annular channel 40 and the interior of the ampule tube or ampule chamber in which medicinal body 26 is confined is effected by means of one or more longitudinally-extending grooves 136, and such structure wherein a plurality of such channels are provided assures that blood may be observed from any position about

the ampule. Plug section 38, of course, may be formed of elastic material similar to that from which the other piston plugs may be molded, or may be, if desired, of different material of either less or greater elasticity.

It will thus be seen that the objects set forth above, among those made apparent from the preceding description, are efficiently attained and, since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

20. 1. A hypodermic syringe ampule for use with a syringe structure including piston post means having a free inner end and a double-ended syringe needle extending longitudinally through said post means, said needle having an inner end extending appreciably beyond the inner end of said post means, the ampule comprising, in combination, a substantially tubular light-transmitting hypodermic syringe barrel slidably receivable of said piston post means, a piston plug slidably received in one end of said ampule and closing the same, and digit-engageable thrust-applying aspirating bulb means closing the other end of said ampule barrel with a body of injectable medicament confined between it and said piston plug, and said bulb means having a laterally-projecting portion abutting the last-mentioned end of said ampule barrel to prevent inward sliding in the latter when manual thrust is applied to said bulb means whereby the thrust is transmitted to said barrel to telescope it forward over said post means, said piston plug being needle-pierceable for puncture by the inner end of said double-ended syringe needle to permit a show of blood in the vicinity of said needle inner end when said bulb is aspirated with the needle bore in communication with a blood vein, said piston plug being slidably up into said ampule by said piston post means with telescope of said ampule thereover for expulsion of contents.
25. 2. A hypodermic syringe ampule comprising a single chamber section of a transparent tube of substantially uniform diameter throughout, a needle-pierceable piston plug slidably received in and closing one end of said tube section and being uncovered to be freely accessible to the piercing end of a double-ended injecting needle and associated piston means for sliding said plug forward into said tube, and an aspirating bulb thrust cap closing the other end of said tube section with a body of medicament confined therein between said cap and plug.
30. 3. A hypodermic syringe comprising, in combination, a casing having an ampule-receptive socket, a plunger post mounted substantially coaxially in said socket and carrying a double-ended hollow injecting needle with the inner end of the latter projecting up from the post, a substantially tubular transparent ampule providing a single medicament-housing chamber between its opposite ends and telescopically received in said socket for telescope down over said post, a needle-pierceable piston plug inserted in the leading end of said ampule to be slid into the latter by said post and having an outer sealing portion pierceable by said inner needle end for communicating the needle bore with the interior of said ampule for a show of blood in the latter, and an aspirating bulb cap closing the trailing end of said ampule to define with the latter said chamber between it and said piston plug, said cap being adapted to aspirate said chamber and serve as a thrust member for said ampule.
35. 4. The hypodermic syringe as defined in claim 3 characterized by said piston plug being provided with blood telltale recess means in communication with said chamber and communicable with the needle bore when said needle inner end is pierced through said sealing portion, said recess means being closed on the side by a portion of the wall of said transparent ampule for observation of blood therein through the latter.
40. 5. The structure as defined in claim 4 characterized by said recess means providing a flow passage between said chamber and the needle bore when said needle in-

ner end is thrust through said piston plug sealing portion with a portion of the passage disposed immediately adjacent the inner face of said ampule wall portion for ready observation of blood flow therethrough.

6. The structure as defined in claim 5 characterized by said recess means comprising a pocket to which said needle inner end is pierceable and a restricted channel in the side of said plug communicating said pocket with said chamber.

7. A hypodermic syringe comprising, in combination, a casing having an ampule-receptive socket, a plunger post mounted substantially coaxially in said socket and carrying a double-ended hollow injecting needle with the inner end of the latter projecting up from the post, a substantially tubular transparent ampule providing a single medicament-housing chamber between its opposite end and telescopically received in said socket for telescope down over said post, blood telltale piston plug means having at least an outer portion of needle-pierceable material and inserted in and closing off the leading end of said ampule to be slid into the latter by said post with telescope of said ampule into said casing for expulsion of

chamber contents through said needle, said piston plug means having at least one longitudinally-extending blood telltale groove in its side surface extending from its inner end to said outer portion and means providing a passage from said groove to the plug means interior at a point to which said needle inner end is pierceable for communication between the needle bore and the ampule chamber, and an aspirating bulb cap closing the trailing end of said ampule to define with the latter said chamber between it and said piston plug means, said cap being adapted to aspirate said chamber and serve as a thrust member for said ampule.
